HEAT EXCHANGING STONE FOR AIR HEATERS AND THE LIKE

Filed Aug. 5, 1927

Inventor:
Otto Strack.

UNITED STATES PATENT OFFICE

OTTO STRACK, OF MUNICH, GERMANY, ASSIGNOR OF ONE-HALF TO THE FIRM OF PFÄLZISCHE CHAMOTTE- UND THORNWERKE (SCHIFFER & KIRCHE) AKTIEN-GESELLSCHAFT, OF GRUNSTADT, GERMANY

HEAT-EXCHANGING STONE FOR AIR HEATERS AND THE LIKE

Application filed August 5, 1927, Serial No. 210,995, and in Germany September 20, 1926.

This invention relates to heat-exchanging stones of the kind, of which a plurality is inserted into an air-heater or the like in order to accumulate the heat of furnace gases or the like and to transmit thereafter this heat to air or another gas. More especially, the improved stones forming the subject-matter of this invention are intended for the production of a heat-exchanging structure having narrow vertical channels or passages, viz. such below 100 mm. clear width, and having only thin walls between the channels or passages, viz. below 50 mm.

Such stones (which may be comparatively long so as to resemble tubes) are only small in section and only little resistible to bending or warping, and there exists, thus, the danger that a stone of any of the constructional forms used at present is bent if the stones carried by it are not located perfectly vertically and centrally on it, the result otherwise being that the upper stones tumble down, are also bent, displace the adjacent stones and cause in the whole very great disorder, whereby the usefulness of the air-heater is severely disturbed, if not the entire heater is rendered useless for the time being.

The object of the invention is to obviate such occurrences, and this object is attained by uniting with each other a plurality of air-exchanging stones having channels or passages of the small diameter, and walls of the slight thickness, above stated, there being obtained a heat-exchanging body having a corresponding plurality of the small channels or passages and between them the thin walls, but being by far more resistible against bending and compression and having such a strength that the heat-exchanging structure composed of these multiple- or compound-stones is completely prevented from collapsing, and the proper service of the air-heater is, therefore, never disturbed.

The invention is illustrated diagrammatically and by way of example on the accompanying drawing on which Figure 1 is a top-view of a multiple- or compound-stone formed by the union of four octangular stones, Figure 2 is a top-view of a modification in which four star-shaped stones are united with each other,

and Fig. 3 is a top-view of another modification composed of four tubular stones.

In Fig. 1 four octagonal stones A are united integrally with each other. Each has a circular channel or passage a of about 70 mm., 55 diameter or less, and between the four stones, or centrally in the multiple-stone A, is a quadrangular channel or passage b of about 50 mm. clear width or less, whereas rectangular grooves c are provided at the four 60 sides of the stone A. It will be obvious without a more detailed explanation that two grooves c of two neighbouring multiple-stones like A form a channel or passage like b, and this is true, of course, of all stones 65 forming the structure built into the heater.

In Fig. 2 three star-shaped stones are uniformly distributed around a central star-shaped stone, all four together forming a multiple- or compound-stone B having four 70 circular channels or passages d and three large grooves e, as well as nine small grooves f. It is also in this case obvious that these grooves will be closed and completed so as to form channels or passages like d by the neighbouring stones that are shaped exactly as the stone B shown.

In Fig. 3 the multiple- or compound-stone C is composed of four tubular stones having each a circular channel or passage g resembling the channels or passages a in Fig. 1 and d in Fig. 2. The grooves h are closed by the neighbouring stones C so as to form channels or passages of the sectional shape i.

The thickness of the walls between the passages or channels is in all cases less than 50 mm.

I wish it to be understood that I do not limit myself to the few examples shown on the drawing. Experts will understand that 90 also other constructional forms are possible without departing from this invention.

I claim:

1. A heat-exchanging stone for heat-exchanging structures in air heaters and the like, said stone comprising a plurality of units 95 each of a regular geometrical figure having a passageway extending axially therethrough, said units being integrally connected together.

2. A heat-exchanging stone for heat ex-changing structures in air heaters and the like, comprising a plurality of units, each of said units comprising a regular geometrical figure in cross section, each of said units having a central passageway therethrough disposed symmetrically with respect to said unit and having non-square corners whereby said units in cooperation with one another provide passageways at said non-square corners, said units being integrally united together.

In testimony whereof I affix my signature.
OTTO STRACK.
